J. GORHAM.
Corner-Iron for Wagon-Bodies.

No. 225,052.

Patented Mar. 2, 1880.

Jackson Gorham.
By Request of Secret.

ATTORNEY

UNITED STATES PATENT OFFICE.

JACKSON GORHAM, OF CRAWFORDVILLE, GEORGIA, ASSIGNOR OF ONE-HALF OF HIS RIGHT TO W. A. LEGWEN, OF SAME PLACE.

CORNER-IRON FOR WAGON-BODIES.

SPECIFICATION forming part of Letters Patent No. 225,052, dated March 2, 1880.

Application filed January 14, 1880.

To all whom it may concern:

Be it known that I, JACKSON GORHAM, of Crawfordville, in the county of Taliaferro and State of Georgia, have invented certain new and useful Improvements in Combined Corner-Iron and Body-Strap for Wagon-Bodies; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to an improvement in a combined corner-iron and body-strap for wagon-bodies, the object being to provide a device which may be produced at a small first cost, and adapted to be readily applied to the 20 corners of wagon-bodies and serve as a body-strap to firmly unite the sides, bottom, and cross-piece beneath the wagon-body, and also to serve as a guide for the reception of the end-gate.

25 To these ends my invention consists in a combined corner-iron and body-strap for wagon-bodies embracing the several details in construction hereinafter described, and pointed out in the claim.

30 In the accompanying drawings, Figure 1 is a view, in perspective, of my improvement. Fig. 2 is a view, in perspective, of the rear portion of a wagon-body having my improvement connected therewith.

35 A represents the side planks of a wagon-body, B the bottom, and C the cross-piece, extending transversely beneath the bottom near the end of the body, said cross-piece projecting outward at the opposite ends, as at a, 40 beyond the side planks.

45 D designates my improved corner-iron and body-strap, and is made in a single piece, either of wrought, cast, or malleable iron, the side flange, E, being of sufficient width to insure a full firm bearing on the end of the side plank, to which it is secured by means of screws, bolts, or rivets b, inserted through holes c in the side flange, E, and fastened to the side plank.

50 The lower end of the side flange is provided with an outwardly-projecting lug or bracket, F, which is secured to the upper side of the projecting end a of the cross-piece C, said bracket or lug extending downwardly a suffi-

cient distance below the side flange to allow 55 of the insertion of the bottom B between the cross-piece C and side plank, A.

Thus it will be observed that the portion of the device thus far described constitutes a strong and reliable body-strap, firmly securing together the side plank, bottom, and cross-piece.

The side flange is made of a width to project rearward of the side plank a distance equal to the thickness of the end-gate, and on 65 the rear edge of the side flange is formed a lateral flange, G, of any desired width, which, in connection with the side flange, constitutes a complete corner-iron and forms a groove 70 for the reception of the end of the end-gate, which latter may be readily removed from the corner-iron, whenever desired, by simply raising it vertically out of the groove.

Both corners of the rear end of the wagon-body are provided with my improved device, 75 as hereinbefore described, which operate to impart strength, stiffness, and durability to the wagon-body, allow the end-gate to be readily inserted and removed, and afford a fine complete finish to the vehicle.

The device may be produced at small cost and of little weight, so that it will not materially add to the cost or weight of the wagon-body, while, on the other hand, it will very much enhance its strength, efficiency, and appearance.

Having fully described my invention, what I claim as new, and desire to secure by Letters Patent, is—

The combination, with the side plank, cross-piece extending transversely beneath the bottom planks, and removable sliding end-board, of the combined corner-iron and body-strap, consisting of the flange E, secured to the side A, and projecting rearwardly beyond its end 90 a distance equal to the thickness of the end-board, the flange G, located at right angles to flange E, and forming a guide for the end-board, and bracket F, extending below the flanges E G a distance equal to the thickness 100 of the bottom board, and secured to the cross-piece C, substantially as set forth.

In testimony that I claim the foregoing I have hereunto set my hand this 5th day of January, 1880.

Witnesses: JACKSON GORHAM.

V. T. SMITH,
C. A. BEAZLEY.
